DRUM SIEVE

Antonius Kufferath, Mariaweiler, near Duren,
Germany, assignor to Neumeyer & Dimond, Inc.,
New York, N. Y., a corporation of New York

Application March 30, 1937, Serial No. 133,768
In Germany April 6, 1936

8 Claims. (Cl. 92—43)

This invention relates to drum sieves of the kind comprising a drum body and a wire mesh jacket fitted over said body. Such drum sieves are used for various purposes, for example, in paper making machinery, and they are known by different terms according to the purposes for which they are employed. In these and other drum sieves, the cylindrical jacket sieve has to be firmly and immovably connected to the drum body, and, as a result, difficulties arise when the sieve jacket has to be replaced by a fresh one owing to wear or other reasons. Since it is desired that the sieve shall tightly engage the drum body, the mounting and removal are accompanied by great difficulties. For this reason also, a sieve can only be employed in connection with the drum body which it fits exactly.

According to the invention, the jacket of a drum sieve consists of wire mesh, the circumference of which is altered by stretching in the longitudinal direction or by rotation around the axis of the drum. This enables metal sieve jackets to be employed which may be mounted and removed very easily and yet are applied to the drum body tightly, without creases or joints. The saving of time resulting from the facility of mounting and pulling off the jackets is, however, not the only advantage resulting from the utilization of the invention. There is the considerable further advantage that the manufacture of the jackets is simplified, since the diameter of the sieve need not correspond exactly to that of the drum body. Moreover, the jacket may still be used after it has become distended by use or repeated mounting and removal, so that the useful life of the sieve jacket is increased. The considerably reduced interruption of work occasioned by the renewal of a sieve is even further reduced to a substantial extent in many cases, since a sieve which has become loose may be tightened while on the drum body. The invention enables the sieve to be reduced in diameter without the necessity of removing it from the drum body for this purpose. Moreover, the mounting and removal of the jacket is such a difficult operation in the known arrangements that in most cases it can only be accomplished with the aid of special tools.

It was proposed to provide arrangements whereby the sieve jacket could be secured to its drum body as a tight fit, but these arrangements utilized a crease or split joint in the sieve jacket for the purpose of tightly fitting it. The joint or crease was unavoidable. In contrast, the jacket according to the invention is free of all

creases or split joints and is variable in its clear diameter, since the variation of the diameter is effected by stretching or rotation.

For example, where a sieve jacket with a sewn or welded seam or a circular woven sieve jacket is used, the ends of this sieve may be engaged in end discs and these may be relatively rotated. After such twisting, those wires of the jacket which were previously parallel to the drum axis will extend diagonally thereto. At the same time the circumference of the sieve is reduced, so that it becomes tightly applied to the drum body. Means for rotating the sieve ends and for subsequently fixing them may be mounted at one or both ends of the drum or of the sieve jacket.

Alternatively, the clear diameter of the jacket may be altered, that is to say, reduced, diminished or decreased to substantially that of the outside diameter of the drum body, by employing a sieve fabric the extent of which is reduced, when longitudinal pull is applied thereto, in a direction at right angles to the pull. The sieve diameter will then be increased when the jacket is compressed, i. e., contracted or shortened. In this condition, the jacket may be easily and quickly mounted and removed. After the mounting, the sieve diameter is reduced by the application of longitudinal pull to such an extent that it becomes tightly applied to the drum body and hugs the periphery of the drum body circumferentially.

According to a further feature of the invention, a sieve jacket the diameter of which is increased or reduced by the application of pressure or pull may comprise a wire mesh with wires extending at an angle to the direction of movement. In such a fabric the warp and weft threads do not extend in a direction parallel and perpendicular to the side edges of the jacket, as in the known sieves or in a sieve jacket the diameter of which is to be varied by rotation as described, but at an oblique angle to both. The angle at which the wires cross one another is varied when the jacket is extended or compressed longitudinally, whereby the clear diameter of the jacket is also varied. Pulling means are disposed at one or both ends of the drum body, whereby longitudinal pull may be exerted upon the sieve. These means may comprise, for example, an end disc or annular ring in which the end of the sieve is engaged, said end disc or annular ring being extensibly attached to the drum body and substantially coextensive in diameter therewith and being moved away from the drum,

for example, by screws which take a point of support on the drum end. This has the effect of making the drum body, or a portion thereof, elongatable. In this manner an end pull may be exerted upon the sieve, to which it yields, the diameter being simultaneously reduced until the sieve becomes tightly applied.

In the accompanying drawings various embodiments of the invention are illustrated by way of example.

In Figure 1, the sieve jacket comprises a fabric 1 the wires of which extend in a direction parallel and perpendicular to the axis of the drum 2. In this arrangement, there is no possibility of applying the sieve jacket tightly to the drum body by rotation or longitudinal pull. In Figure 3 two end discs 4 are provided. At the left hand end the end disc of the drum body is indicated at 6 and is shown in dotted lines. One or both of the end discs 4 may be rotated relatively to one another, whereby the wires, which originally extend in directions parallel and perpendicular to the axis of the drum (Figure 3), assume a slanting position after the rotation, as shown in Figure 4, and the diameter of the jacket is reduced. In order that the end discs 4 shall not spring back into their original position, they are secured in position with reference to the drum end disc, for example, by being screwed thereto.

An example of the mounting of the sieve jacket on the end discs is shown in Figure 2 in connection with a sieve fabric, which undergoes contraction transversely to the longitudinal direction when pull is applied in that direction. The pulling means, shown only at the left hand end of the sieve jacket, comprises the fitting disc 4 with screw bolts 5. The pulling means, like the rotational tensioning means may, of course, be disposed at both ends of the sieve jacket. The screw bolts 5 are supported on the end face 6 of the drum body, and sieve 3 is pushed over the drum body in a direction from right to left. Its left hand end is then placed over the fitting disc 4 and is clamped fast thereon by a clamp ring 7 with the aid of the screw 8, these clamping means being shown by way of example. The sieve 3 is then pulled longitudinally with the aid of the screw bolts 5, until it is tightly applied. The screw bolts 5 may also be utilized for subsequently tensioning the sieve on the drum body.

The foregoing examples are not intended to restrict the invention to drums with terminal trunnions, the invention being equally applicable to drums with open ends. Moreover, the term "drum sieve" is not intended to restrict the invention to drums wherein a tight jacket is employed for the sake of its sifting properties, since jackets of other kinds may also be mounted and fixed according to the invention.

Figure 5 shows diagrammatically part of a paper making machine, which includes a dandy roll 10 which runs on the wire cloth 11. The wire cloth is maintained in stretched position by the guide rolls 12. Reference characters 13 are suction boxes, 14 are tube rolls and 15 is the take-up roller for the finished paper web.

Figures 6 and 7 show the application of the invention to sieve drums running on rollers or rotating in a bearing 18.

Figure 6 shows in section one end of an open end drum, showing the drum jacket 20 comprising a wire fabric and secured to an end ring 21. The end of the sieve jacket is fixed by means of

a clamping ring 22 connected to the end ring 21 by means of screws 23. The end piece of the drum body comprises a cylindrical member 24 with a wide flange 25. After the end of the sieve has been clamped fast between the rings 21 and 22, the distance between the ring 21 and the flange 25 may be increased by means of the threaded spindles 26 engaging in tapped bores of the flange 25, and thereby the sieve may be stretched. The spindles 26 are secured by means of a lock nut 27. The drum body has rods or tubes 29 extending in a direction parallel to the axis of the drum, said tubes or rods being supported by stiffening rings 30 or the like.

Figure 7 shows the end of a sieve drum with bearing mounting 18 and an alternative tensioning device according to the invention. The end of the sieve jacket surrounds an end ring 32 having a tapered surface 33, over which a holder ring 34 is placed. The holder ring has a correspondingly tapered inner surface. The free end of the sieve jacket is placed between the two tapered surfaces, the outermost edge of the jacket being enlarged, if desired, by beading, folding or casting out with lead, in such a way as to fill up the annular groove 35. By pull of the jacket 20 towards the right and of the parts 33 and 34 to the left, the sieve fabric 20 is clamped fast automatically. This method of fixing has the advantage that it may be easily released at any time.

By means of an end disc 36 and a thread 37 on the shaft 23, an axial pull may be exerted upon the sieve 20. For this purpose the surface 38 is formed, for example, for the reception of a lever or spanner, whereby the rotation of the end disc 36 is facilitated. During this operation the parts 32 and 34 may be held fast, so that the sieve is not rotated, but merely stretched. However, the end of the sieve may also be rotated together with the end disc 36. The end disc may be fixed against movement in any desired position by means of the lock nut 40.

I claim:

1. A device of the character described, comprising a drum body and a wire netting with changeable mesh formation, the wires of said netting extending in a direction neither parallel nor perpendicular to the axis of said drum body, said netting held loosely on said body, and means for changing the mesh formation of said wire netting by stretching said netting in a longitudinal direction thereby reducing its diameter and at the same time forcing said netting against the circumference of said drum body.

2. A device of the character described, comprising a drum body and a wire netting hugging the circumference of said body, said wire netting having a mesh whose wires extend in a direction neither parallel nor perpendicular to the axis of said drum body, and operable means associated with said drum body and said wire netting for changing the mesh of said netting on said drum body and thereby reducing the diameter of said netting by stretching said netting in an axial direction whereby said netting is caused to hug the circumference of said drum.

3. A drum sieve for paper making machines comprising an open, rotatable, cylindrical drum body, an annular ring extensibly attached to at least one end of said drum body and substantially coextensive in diameter therewith, a wire-mesh cylinder mounted upon the periphery of said drum body, the wires composing said cylinder extending in a direction neither parallel nor

- perpendicular to the side edges of the cylinder, means for securing the end of said wire-mesh cylinder to said annular ring, and means for adjusting the distance between said annular ring and the end of said drum body whereby the length of said wire-mesh cylinder may be increased, thereby causing its diameter to decrease to substantially that of the outside diameter of the cylindrical drum body.
- 5 4. A drum sieve for paper making machines comprising an open, rotatable, cylindrical framework having an end portion thereof elongatable and a remaining portion non-elongatable, a wire-mesh cylinder welded along a line substantially parallel to its axis mounted upon the periphery of said framework, the wires composing said cylinder extending in a direction neither parallel nor perpendicular to the side edges of the cylinder, means for attaching the ends of said wire-mesh cylinder to said framework, means for elongating said framework between such points of attachment thereby axially stretching said wire-mesh cylinder and thus decreasing its diameter to substantially that of the 10 outside diameter of the cylindrical framework and causing it to hug the periphery of said framework circumferentially, and means for securing said wire-mesh cylinder to the non-elongatable portion of said framework.
- 15 5. A drum sieve for paper making machines comprising a shortenable, rotatable, open, tubular framework, a wire-mesh sleeve mounted tightly upon the periphery of said framework and secured at the ends of said framework, said sleeve having wires positioned at an oblique angle to the ends thereof and crossing each other at an oblique angle, and means for shortening said framework thereby axially shortening said sleeve and accordingly increasing its diameter 20 to facilitate its removal from said framework.
- 25

6. A drum sieve for paper making machines comprising a rotatable, open, tubular framework, a wire-mesh sleeve mounted tightly upon the periphery of said framework and secured at the ends of said framework, said sleeve having wires positioned at an oblique angle to the ends thereof and crossing each other at an oblique angle, and means for disattaching said wire-mesh sleeve from said framework thereby permitting axial contraction of said sleeve and a consequent increase of its diameter to facilitate the removal of said wire-mesh sleeve from said framework.

5 7. A drum sieve for paper making machines comprising an extensible, rotatable, open, tubular framework, a wire-mesh sleeve mounted upon the periphery of said framework with the wires composing said sleeve at an oblique angle to its ends, means for attaching said sleeve to said framework, and means for elongating said framework between such points of attachment thereby axially stretching said sleeve and providing a tight circumferential fit of the wire-mesh sleeve upon the periphery of the framework.

15 20 25

8. The method of mounting a cylindrical sieve with deformable mesh to a drum body, comprising passing a loosely fitting sieve formed of two sets of helically disposed wires crossing each other over the drum body and fastening its end parts onto a drum body, thereafter changing the wire mesh formation by moving the end parts longitudinally relative to each other, thereby substantially equally tensioning each set of the wires of the sieve netting relative to the other, 30 thereby reducing the diameter of the sieve until its inner surface is tightly drawn against the circumference of the drum body.
